US00D829828S

(12) **United States Design Patent** (10) **Patent No.:** **US D829,828 S**
McLachlan et al. (45) **Date of Patent:** ** *Oct. 2, 2018

(54) **HANDHELD TOUCH OBJECT**

(71) Applicant: **Antsy Labs, LLC**, Dacono, CO (US)

(72) Inventors: **Matthew McLachlan**, Dacono, CO (US); **Mark McLachlan**, Frederick, CO (US)

(73) Assignee: **Antsy Labs, LLC**, Dacono, CO (US)

(*) Notice: This patent is subject to a terminal disclaimer.

(**) Term: **15 Years**

(21) Appl. No.: **29/615,501**

(22) Filed: **Aug. 29, 2017**
